(57) **CLAIM**

The ornamental design for a sneaker, as shown and described.

DESCRIPTION

FIG. 1 is a front perspective view of a sneaker showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The portions of the sneaker shown in broken lines represent thread stitching and do form a part of the claimed design.
